C. J. TRAVERS,
BASE FOR CHAIRS, &c.,
APPLICATION FILED OCT. 1, 1919.

1,333,949.

Patented Mar. 16, 1920.

UNITED STATES PATENT OFFICE.

CHARLES J. TRAVERS, OF PORT WASHINGTON, WISCONSIN.

BASE FOR CHAIRS, &c.

1,333,949.

Specification of Letters Patent. Patented Mar. 16, 1920.

Application filed October 1, 1919. Serial No. 327,724.

To all whom it may concern:

Be it known that I, CHARLES J. TRAVERS, a citizen of the United States, residing at Port Washington, in the county of Ozaukee 5 and State of Wisconsin, have invented new and useful Improvements in Bases for Chairs, &c., of which the following is a specification.

This invention relates to improvements in 10 wooden bases for tilting and revolving-chairs, tables, costumers, stands, etc., but is primarily intended as a chair-base.

The principal objects of the invention are to produce a base for the purposes mentioned, 15 which while comparatively inexpensive and simple to manufacture, yet, by reason of its peculiar novel construction, is possessed of very great strength and durability and is capable of performing its function of a base 20 and of sustaining excessive weight without danger of becoming loosened at its joints and consequently spreading and collapsing.

With these and other objects in view, the invention consists of a chair or other base 25 formed of wood, the inner ends of the legs of which are provided with a series of preferably reduced parallel spaced-apart tenons arranged in vertical series and forming intermediate mortises, the inner walls of 30 which are at right angles to the vertical sides of the tenons, and in intermediate connecting filler-blocks, substantially triangular in cross-section and having alternating tenons and mortises, the former being of 35 such shape as to enter between the tenons of the legs and occupy the mortises thereof, the opposite sides of said filler-blocks having external shoulders overlapped or engaged by corresponding shoulders produced 40 at the opposite sides of the legs, caused by a lateral reduction of the tenons of the latter, whereby a withdrawal of said blocks is successfully resisted by the legs.

Referring to the drawing: 45 Figure 1, is a top-plan view of a base constructed in accordance with my invention, the outer ends of the legs being broken away;

Fig. 2, is a detail in inner end elevation of 50 one of the legs;

Fig. 3, is a similar view of one of the connecting filler-blocks;

Fig. 4, is a top-plan view of the inner portion of one of the legs; and

55 Fig. 5, is a detail in plan of one of the connecting filler-blocks.

Similar numerals of reference indicate similar parts in all the figures of the drawing.

The legs, 1, may be of any style or design desired, and each is provided at its inner end with a vertical series of spaced-apart longitudinally disposed tenons, 2, of uniform thickness, and combining to produce intermediate transverse mortises, 3. 60 65 The ends of these tenons are squared or at a right angle to the leg on which they are formed, as indicated by the dotted lines *a*, (Fig. 1,) and as shown by full lines, Fig. 4, the sides of said tenons are preferably parallel with each other and also with the sides of 70 the legs on which they are formed.

The tenons are somewhat reduced laterally, as compared with the legs on which they are formed, so that there is, as a result 75 of such reductions, formed at the opposite sides of each leg, at its juncture with the tenons, right angularly disposed vertical stop-shoulders 4.

The connecting filler-blocks, 5, (shown 80 in detail in Figs. 3 and 5,) are of such shape in cross-section as will adapt them to fit snugly between the vertical sides of the tenons of two adjacent legs and in advance of the shoulders 4 thereof. To this end, the 85 connecting or filler-block proper, is substantially triangular, when viewed in cross-section, although its outer face, or what would be the base of the triangle, may be formed concaved, convexed or of other shape, the 90 only essential being that the opposite vertical edges of each filler-block be provided with a vertical shoulder, 6, corresponding with and adapted to be overlapped or engaged by the shoulder, 4, of the adjacent 95 legs 1; so that, as will be obvious, the parts having been assembled, it will be impossible for the blocks to be removed without a previous removal of the legs.

Projecting from the inner angularly disposed faces of each block 5, is a series of spaced-apart tenons 7, the opposite sides or ends of such tenons being substantially triangular, and therefore having their outer faces adapted to aline against the vertical 100 transverse walls of the mortises of the legs, the tenons of one block abutting with those of the next adjacent blocks, so that the two tenons of adjacent blocks will meet and abut at the center of the mortises of the legs and 105 completely fill the same, (see Fig. 1).

The tenons of the legs, being formed as

shown, for the purpose of simplifying the operations by which they are produced, do not interlace or connect, but simply meet at their inner corners, as indicated by dotted lines in Fig. 1. For connection of the legs, the connecting filler-blocks are depended upon, each block, as will be seen, overlapping and occupying substantially one-half of the area of the two adjacent legs. The 10 tenons of the connecting filler-blocks are at variance or staggered with relation to the tenons of the legs, so that when the legs and blocks are assembled, the upper and lower surfaces of these parts are flush.

15 It will be understood that there may be employed upper and lower metal-plates, ordinary screws being inserted through the plates and into the tops and bottoms of the legs, for the purpose of preventing the latter from spreading under the weight or load. As is usual, said plates may or may not support a metal hub for the purpose of accommodating the supporting standard rising from the base and adapted to support a chair-seat, costumer, table, or other article.

30 The tenons and other portions of the legs and blocks, the surfaces of which meet, are glued together, after which the base, as thus formed, and previous to the application of the upper and lower plates, is bored centrally, as at 9, such bore being formed partly in the ends of the tenons of the legs and partly in the tenons of the blocks. If preferred, however, the boring operation may be omitted, so that there will be left a bore octagonal in cross-section, formed by the meeting or inner ends of the tenons and legs.

40 From the foregoing description in connection with the accompanying drawing, it will be apparent that I have produced a chair-base of neat design and one possessing very great strength and tendency to resist spreading under all ordinary circumstances and conditions, and wherein the principle of interlacing the connecting-blocks with the legs is carried out with as little expense in the operation of manufacture as possible, the saw-cuts being all straight and there being formed no small shoulders and recesses for the purpose of fitting the parts and requiring additional time-consuming operations. Moreover, the sides of the tenons of the legs being parallel to the sides of the legs themselves and not made wider for the purpose of interlacing with adjacent legs, results in a saving of material in forming said legs; so that, as will be obvious, while 50 my base is capable of sustaining a maximum load without danger of spreading and possesses unusual durability, yet it is capable of being manufactured at a reasonable cost, there being unnecessary in such manufacture of any excess of operations.

It will be noted that the grain of the wood from which the connecting filler-blocks are formed is disposed lengthwise the block, which, as will be apparent, disposes said grain at an angle to the grain of the wood 70 from which the legs are formed, so that by such disposition, the greatest strength is secured. If desired, dowel-pins or screws may be inserted through the interlacing tenons of the filler-blocks and legs, but it is 75 thought merely gluing them together will afford ample security in connection with the top and bottom plates generally used.

Having described my invention, what I claim is:

1. A chair or other base, comprising a series of legs having at their inner ends inwardly disposed tenons, laterally reduced to form opposite vertical shoulders at the junctures of the tenons and legs and spaced 80 apart to produce intermediate transverse mortises, and connecting filler-blocks arranged between said legs, said filler-blocks having their opposite outer faces overlapped by the vertical shoulders of the legs and 85 having their inner sides provided with a series of tenons spaced apart to form intermediate mortises, said tenons being staggered with relation to the tenons of the legs and overlapping the same by entering the 90 mortises thereof.

2. A chair or other base, comprising a series of legs having at their inner ends inwardly disposed tenons, and connecting filler-blocks arranged between said legs, said 100 filler-blocks having their inner faces provided with a series of tenons spaced-apart to form intermediate mortises, said tenons being staggered with relation to the tenons of the legs, the sides of the tenons of two 105 adjacent blocks meeting and abutting in the mortises of the legs in which they are located and paralleling each other.

3. A chair or other base, comprising a series of legs having at their inner ends inwardly disposed tenons and at the juncture of the same with the legs provided with vertical shoulders, and connecting filler-blocks arranged between said legs and having their opposite side-edges overlapped by said shoulders of the legs, said filler-blocks having 110 their inner faces provided with a series of tenons and intermediate mortises, staggered with relation to those of the legs, said tenons of the filler-blocks being laterally disposed 115 so as to engage the mortises of the legs.

4. A chair or other base, comprising a series of legs having at their inner ends inwardly disposed tenons and at the juncture of the same with the legs provided with vertical shoulders, and connecting filler-blocks arranged between said legs and having 125 their opposite side-edges engaged by said shoulders of the legs, said filler-blocks having their inner faces provided with a series 130

of tenons staggered with relation to those of the legs and adapted to enter the mortises of said legs, and having their edges meeting and abutting and disposed parallel within 5 said mortises.

5. A chair or other base, comprising a series of legs having at their inner ends inwardly disposed tenons and intermediate mortises having inner transverse walls, and intermediate connecting filler-blocks, triangular in cross-section and having their walls, coinciding with and abutting against the opposite sides of the tenons, and provided at their inner faces with opposite tenons having substantially triangular ends adapted to enter and abut in the mortises of the legs and to parallel each other and the wall of 15 said mortises.

6. A chair or other base, comprising a series of legs having at their inner ends inwardly disposed tenons and intermediate mortises having inner transverse walls, and intermediate connecting filler-blocks, triangular in cross-section and having their walls 20 coinciding with and abutting against the opposite sides of the tenons, and provided at their inner faces with opposite tenons having substantially triangular ends adapted to enter and abut in the mortises of the legs and to parallel each other and the wall of 25 said mortises.

positive faces or sides of the tenons of the legs, and provided at their inner faces with laterally extended tenons having triangularly shaped outer ends entering and abutting and paralleling each other in said mortises and the transverse walls of the same. 30

7. A chair or other base, formed of wood, and comprising legs having inwardly disposed tenons, and intermediate connecting filler-blocks tenoned at variance with those 35 of the legs and interlacing therewith, said blocks having the grain of the wood from which they are made disposed at an angle to the grain of the wood of said legs.

8. A chair or other base, comprising a series of legs provided at their inner ends with inwardly disposed tenons, and connecting filler-blocks arranged between said legs, said blocks having their inner faces provided with a series of tenons spaced apart 45 to form intermediate mortises, said tenons being staggered with relation to the tenons of the legs.

CHARLES J. TRAVERS.
